UNITED STATES PATENT OFFICE.

HENRY H. GRIDLEY, OF HOLYOKE, MASSACHUSETTS.

GAS-REGULATOR.

SPECIFICATION forming part of Letters Patent No. 340,112, dated April 20, 1886.

Application filed January 18, 1886. Serial No. 188,962. (No model.)

To all whom it may concern:

Be it known that I, HENRY H. GRIDLEY, a citizen of the United States, residing at Holyoke, in the county of Hampden and State 5 of Massachusetts, have invented new and useful Improvements in Gas-Regulators, of which the following is a specification.

This invention relates to improvements in gas-regulators; and the invention consists in 10 the peculiar construction and arrangement of parts, as hereinafter fully described, and pointed out in the claims, the object being to simplify and reduce the number of the parts in such machines, whereby their efficiency is 15 increased and the necessity of frequent repairs is obviated.

In the drawings forming part of this specification, Figure 1 illustrates in a vertical sectional view a gas-governor embodying my improvements. Fig. 2 is a transverse section of the valve-case. Fig. 3 is a transverse section of the valve-cage and the valve-spindle above the valve in Fig. 1, showing the upper end of the latter in plan view.

25 In the drawings, *h* is the valve-case, having a screw-threaded inlet-opening at its lower end and a like outlet-opening in its side. The ordinary gas-conducting pipes are attached to the regulator at said openings, the service-pipe 30 to said inlet, and that which supplies gas to the burners to the outlet. The upper end of the valve-case is screw-threaded to receive the nut *K*, having a central opening through it, as shown, and at the lower end of said screw-thread is an annular seat, 18.

The valve-case has cast in it the hollow cage-receiver *n*, of substantially rectangular form in cross-section, whose upper wall has one end united to the side of said case, and its 40 lower wall is united to the upturned edge of the diaphragm *m*, which extends in a horizontal direction across the case *h*, just above the inlet of the latter, and between the said upturned end of said diaphragm and the adjoining 45 inner side of the case *h* is thereby formed a gas-passage, *z*, through which gas flows from the said inlet-opening to the interior of the cage-receiver *n*. The upper and lower walls of the latter are provided with circular perforations to receive the valve-cage *e*, and circular

seats 16 and 17 for the flanges on the valve-cage, as below described. Said valve-cage consists of a head, 13, having a flange formed around its border, which is seated on said seat 18 of the case *h*, and from it projects upwardly the tubular stem *e'*, and attached to its under side are the downhanging legs 6 55 6, having the laterally-projecting flanges 7 and 9 surrounding them, said flanges being seated on the upper sides of said upper and lower walls of the cage-receiver *n*. Said legs 6 (shown in cross-section in Fig. 3) extend through said lower wall of the receiver *n*, and form between their inner edges a guide for the lower end, 3, of the double-headed valve 60 *o*, the lower seat for the latter being formed at 5, between said legs, and the seat for the upper end, 2, of said valve being formed at 4, also between the legs 6. The upper end, 2, of said valve *o* is made of less diameter than its 65 lower end, in order that said upper end may be passed through the opening surrounded by the valve-seat 5, to place it within the cage. The gas-passages, as indicated by the arrows in Fig. 1, are between the legs 6 at 12. A 70 glycerine-cup, *b*, containing a suitable quantity of glycerine, *f*, is soldered or otherwise suitably secured to the upper end of the said tubular stem *e'*, and that portion of the bottom of the cup *b* directly over the center of said 75 stem is perforated to let the valve-spindle *d* pass freely therethrough, and surrounding said central perforation are a series of other 80 perforations, *i*, sufficient in number to form in the aggregate an unobstructed gasway for 85 the free passage of gas through the stem *e'* into the inverted-cup-shaped gas holder *a*, and vice versa. Said gas-holder *a* is secured to the upper end of the spindle *d* by the nuts *x x*, and the lower edge of the holder dips into the 90 glycerine *f*, as shown, thereby sealing the gas-holder in the usual manner. The valve *o* is attached to the lower end of the spindle *d*, as shown, the latter extending from the apex of the gas-holder through a portion of the bottom of the glycerine-cup and the stem *e'* to within the valve-cage *e*. The bottom of the 95 glycerine-cup *b* is elevated above the level of the glycerine *f*, in order to provide a gas-inlet therein through perforations *i*, without pro- 100

viding, as heretofore, a "stand-pipe" within the cup, passing up through the glycerine.

c is a cover to cup *b*.

The above-described construction of said valve-cage and the receiver *n*, together with the nut *K*, provides for securing said cage, valve, and stem, glycerine-cup, and gas-holder to the valve-case *h* by a single instrumentality--viz., the nut *K*. The seats on the case *h* and receiver *n* for the flanges 13 and 7 and the cage *c* are all turned true, and their rubber gaskets 14, 8, and 10 are interposed between said flanges and seats, and the nut *K* being screwed against the head 13, all of said bearing-faces are brought closely together, and gas-tight joints are formed between them. The course of the gas entering the said inlet to the case *h* is as indicated by the arrows in Fig. 1, and the gas enters the open end of the receiver *n*, passes between the legs 6 of the valve-cage, and thence up and down through the valve seat openings therein, passing between said legs, between the head 13 and flange 7, and under the receiver *n* to the outlet of the case *h*. The gas freely passes up the stem *e* into the gas-holder *a*, and the variations of pressure either in the supply or by reason of the consumption of more or less gas causes a movement of the gas-holder up and down, and a consequent movement of the valve *o* toward and from its seats, thereby restricting the gas-passages between the latter and the valve when there is an excess of pressure, and increasing the size of said passages when the pressure is low, thereby regulating the quantity of gas which may pass through the machine, so that there is little, if any, variation

thereof under different pressures, the burners being the same under said varying conditions.

What I claim as my invention is—

1. A gas-regulator consisting of the following elements, viz: a valve-case, *h*, having the requisite inlet and outlet openings and a screw-threaded opening in its upper side, through which the valve-cage is introduced, and having a hollow cage-receiver, *n*, formed therein, one end of which is open to receive gas, and whose upper and lower walls are perforated to receive the valve-cage, combined with a valve-cage, *e*, having side openings and valve-seats therein and flanges thereon to bear on said walls of the receiver, and having the head 13, provided with the tubular stem *e*, the nut *K*, the double-headed valve *o*, the gas-holder *a*, the valve-spindle *d*, connecting the latter and said valve, and the glycerine-cup *b*, permanently attached to the upper end of said hollow stem, substantially as set forth. 40 45 50 55

2. The valve-case *h*, having the hollow cage-receiver *n* therein, the valve-cage *e*, passing vertically through said receiver and provided with two valve-seats and the hollow stem *e*, the nut *K*, securing said cage to the case *h* and to said receiver, the double-headed valve *o*, the gas-holder *a*, the spindle *d*, passing through said stem and connected to the said holder and valve, and the glycerine-cup *b*, permanently attached to said hollow stem, combined and operating substantially as set forth. 60 65

HENRY H. GRIDLEY.
